J. CONTENTO.
NON-SLIPPING SOLE.
APPLICATION FILED APR. 2, 1920.

1,365,767.

Patented Jan. 18, 1921.

Inventor:

JOSEPH CONTENTO

By Harry H. Allen
attorney.

UNITED STATES PATENT OFFICE.

JOSEPH CONTENTO, OF ALBANY, NEW YORK.

NON-SLIPPING SOLE.

1,365,767.

Specification of Letters Patent.

Patented Jan. 18, 1921.

Application filed April 2, 1920. Serial No. 370,759.

To all whom it may concern:

Be it known that I, JOSEPH CONTENTO, a citizen of the United States, and a resident of the city of Albany, in the county of Albany and State of New York, have made certain new and useful Improvements in Non-Slipping Soles, of which the following is a specification.

As is well known, the sole of an ordinary shoe or boot is made of leather and has a flat surface. Soles of this character give the wearer slight assistance in steadyng himself on a slippery sidewalk or road unless the same be provided with some means to prevent slipping. Moreover the sole of a shoe of the usual type possesses no resilient or cushioning properties of any degree. To produce an attachment for soles that will have resilient qualities and also prevent the wearer from slipping is the object of my invention.

In my invention, I have in a sense utilized the theory of the hoof of a horse in producing a device to prevent sliding or slipping when the same is attached to the sole of a shoe or boot worn by the wearer.

Any one who will examine a horse's hoof will see that the bottom of the same is not a plain surface or a flat surface as is the case with the sole of an ordinary boot or shoe, but is hollowed out, or, in other words, there is a depression in the hoof of a horse that enables him to obtain a firm grip on a dirt highway.

I have utilized this principle in the production of my sole attachment and in constructing the same I form it preferably in a U shape substantially, or, in other words, on the general lines of a horse shoe. By a U or horse shoe shape, I mean any construction that when applied to the sole of a boot or shoe permits of an open space being formed between different sides of the attachment, this space being open at one end or entirely closed by the arms or walls of my attachment according to the manner in which the arms of the attachment are bent or manipulated when the said attachment is fastened to a sole as will be subsequently pointed out.

A most important feature of my invention lies in the provision of means by which the attachment may be quickly and easily attached to a sole by the use of a minimum number of fastening devices and moreover by which a tight joint between the sole and

the attachment may be secured. This is accomplished by concaving the under side of my attachment which, as will be clear, causes the parts to flatten out and make a tight joint when nailed in position, all of which will be explained later.

Non-slipping and wearing devices may also be applied to my attachment shown in the type of my invention illustrated in the accompanying drawing in which Figure 1 is a bottom view of an attachment embodying my invention. Fig. 2 is a cross-section on the line 2—2 of Fig. 1. Fig. 3 is a top plan view and Fig. 4 a section on line 4—4 of Fig. 1 and Fig. 5 another view of my device.

In said drawings the numeral 1 denotes a non-slipping attachment of a configuration comprised within my invention.

The attachment 1 is bifurcated, that is to say, it has two longitudinal sides 2 and 3, which are connected together by what I may call, for purposes of description, a transverse portion 4.

The sole is provided at the toe portion with a non-wearing element 5, such, for instance, as canvas, and on one of its longitudinal portions or legs the said attachment is provided with another non-wearing portion 6 and suitably disposed on the portions 2 and 3 are resilient members such as plugs 7 made of rubber or similar material. Said plugs 7 can be independent of the attachment or cast integral therewith as will readily be understood.

It will be noted, see Fig. 2, for instance, that my bifurcated attachment is concaved or hollowed out as at 8 on its underside and that its upper side 9 is convex. The concaved portion 8 may extend entirely around both the longitudinal and the transverse portions of the attachment as shown in Fig. 3 and the attachment is attached to the underside of a shoe or boot by means of suitable fastening devices such as nails or screws which are to be inserted through said attachment through perforations 9, which are shown as being in the central portion of the non-slipping or rubber plugs, but it will be readily understood that such holes can be disposed at any portion of the attachment.

In order to prevent the fastening devices from being torn loose from the attachment, a washer as 10 (see Fig. 4) is embedded in the attachment around a perforation through

which a fastening device is inserted. It will be seen by this structure that the head of the nail or other fastening device will impinge directly against the washer and this will prevent the sole being torn loose from the nails or screws which hold it.

My device can be made of resilient material, such as leather, rubber or fiber, and it will be noted that the rim constructions of

10 the attachment are extended somewhat as at 11 from the main body. This construction makes provision for attaching the attachment to different sizes of boots or shoes as said portion 11 can be cut to make a

15 proper fit and inasmuch as it is readily understood that the attachment is made of resilient material the longitudinal portions may be bent inwardly or from one another in order to fit the various sizes of shoes.

20 My improved non-slipping attachment may be quickly attached to the bottom of a shoe or boot by nailing the same in place. As will readily be understood and as previously referred to, by having the under side

25 of the device as at 8 concave in cross-section it will be clear that a minimum number of nails or screws may be used and as when the device is nailed the same is flattened this concave portion 8 will cause the

30 attachment to make a very tight joint with the sole of a boot or shoe. This feature I regard as very important as it will be readily seen that my attachment can be quickly nailed in place and that there will be no

35 occasion for sewing or cementing as is usually the fact when attachments of this type are placed in position on the soles of boots or shoes. It will furthermore be clear from an inspection of Fig. 1 that inasmuch

40 as the device is made of resilient material the portions 2 and 3 of the device will or may be moved toward or from one another to fit various sizes of shoes. It will also be clear that there will always be an air pocket

45 or an air space 10 left between the sides of the device and that this space will be closed at one end and open more or less at the other end, that is to say, the size of the opening into the air space formed by the walls of the

50 device when the same is attached to a shoe will depend upon the distance between the parts 2 and 3 when the same are adjusted to the size of the shoe. It will be clear, however, that when my device is in place the

55 walls of the portions 2 and 3 may be sep-

arated or under certain conditions they may meet. In the latter contingency the air space 10 would be closed. It will be clear, however, that the type of attachment illustrated and described in this application is 60 of a resilient bifurcated type that is capable of adjustment to various sizes of shoes or boots and that by reason of its concave under surface is capable of being tightly applied to the bottom of a boot or shoe. 65

When in place and in use the resilient qualities of the device afford the user ease in walking and the configuration of the attachment providing, moreover, the space 10 affords means for the prevention of slipping. 70

The sides of the device may be carried to rather a sharp edge as shown at the portions 11 for instance in Figs. 4 and 5. When thus fashioned the attachment is difficult to see when attached to the sole of a boot or shoe, 75 that is to say, when viewed from the side.

From an inspection of Fig. 5 it will also be seen that the said attachment is shown convexed longitudinally. It will also be seen that I have shown the attachment as 80 convexed on its top surface. By convexing the attachment longitudinally as a whole facility is afforded for attaching it to the sole of an ordinary boot or shoe which is always more or less bent. 85

Having illustrated and described my invention, what I claim as new and desire to secure by Letters Patent of the United States is as follows:

1. A non-slipping attachment for shoe soles which is made of resilient material of a U or horse shoe shape substantially, said attachment having its attaching surface concaved or hollowed out, intermediate its entire periphery, and its tread surface convex 90 in cross-section, the entire sole being convex longitudinally on its tread face and concaved longitudinally on its attaching face. 95

2. A non-slipping attachment for shoe soles which is made of resilient flexible material and of U or horse shoe shape, the said attachment having its attaching surface concaved or hollowed out, intermediate its periphery, and its tread surface convex in lateral cross-section, substantially as de- 100 scribed. 105

JOSEPH CONTENTO.
